A. GOODELL

SANITARY WALL TILE

Filed Aug. 10, 1927

UNITED STATES PATENT OFFICE.

ALFRED GOODELL, OF ROCKFORD, ILLINOIS.

SANITARY WALL TILE.

Application filed August 10, 1927. Serial No. 212,052.

This invention relates to certain novel improvements in sanitary wall tiles.

The salient object of this invention is to provide a wall covering which may be expeditiously installed and which may be arranged in position so as to present a very neat appearance.

Another object of the invention is to provide a wall covering which when properly arranged will present a substantially water proof surface.

A further object of the invention is to provide a wall covering which may be easily cleaned and which will be so arranged as to prevent the accumulation of foreign matter behind the front surface of said tile.

Other objects will appear hereinafter.

The invention consists in the novel combination and arrangement of parts to be hereinafter described and claimed.

The invention will be best understood by reference to the accompanying drawings, showing the preferred form of construction and in which:

Fig. 1 is a front elevational view of a typical installation of my wall covering tile;

Fig. 2 is a vertical sectional view of a typical installation of my improved wall covering tile;

Fig. 3 is a perspective view of the preferred form of construction of my improved wall covering tile;

Fig. 4 is a perspective view of the main member of my improved tile construction;

Fig. 5 is a perspective view of an auxiliary member employed in the tile construction; and

Fig. 6 is a perspective detail view of the form of tile employed adjacent the floor.

Fig. 7 is a perspective view of a modified form of the invention.

Referring to the drawings wherein the preferred embodiment of my invention is illustrated I depict a wall 10 which may be constructed in any approved manner. In order to provide a water-proof surface for this wall 10 I arrange a plurality of tiles 11 over the surface thereof. These tiles 11 may be constructed in any desired way and may be formed either of metal, vitreous material, or the like. The embodiment of the invention illustrated in the accompanying drawings is formed of metal and this form will be described herein but it is to be understood that by making changes which will be readily

apparent to anyone skilled in the art any other form of material might be substituted therefor.

The tiles 11 embody a main member 12 which includes a front surface 13 and which has a portion 14 bent so as to be substantially at right angles to the front portion 13, and this right angularly extending portion 14 terminates in a portion 15 which is disposed substantially parallel to the surface 13 but which extends but a short distance below the portion 14. The opposite end of the surface 13 from the portion 14 includes a right angularly extending portion 16 which is disposed substantially parallel to the portion 14 but which is foreshortened. The tile which has just been described is adapted to be used in the top row of tiles and will be referred to hereinafter as the crown tiles. On the wall 10 near the upper part of the portion to be covered by the tiles 11 suitable headed screws 17 are fastened into the wall 10. The portion 15 of the crown tiles has a serrated edge which includes the recesses 18. The recesses 18 are adapted to be seated over the screws 17 in the manner depicted in Fig. 2 so as to mount the crown tiles in position. In Fig. 5 a brace member 19 is depicted which includes parallel surfaces 20 and 21 which are disposed to lie in different planes and which are connected by a portion 22 which is disposed angularly with respect to the surfaces 20 and 21. As is clearly shown in Figs. 2 and 3 the surface 20 of the member 19 is secured to the rear side of the face portion 13 of the tiles 11 at substantially the central portion thereof. This brace member 19 may be secured in position either by spot welding, riveting or other suitable securing means. It is to be understood that if vitreous material is employed the brace member 19 might be secured in position by employing a suitable adhesive medium. The portion 22 of the brace member 19 is such that when the surface 20 is secured to the tiles in the manner described the surface 21 will be disposed so as to be in abutment with the wall 10 so as to dispose the face 13 substantially parallel but spaced away from the wall 10. The surface 21 of the brace member 19 has a plurality of holes 23 formed therein through which suitable securing devices such as the nails 24 may be extended so as to fasten the brace members securely to the wall 10 so as to rigidly anchor the tiles in position.

As has been stated the portion 16 of the

5 tiles is shortened and this causes a space to be defined between the end of this portion 16 and the brace member 19 as is clearly shown in Fig. 2. The majority of the tiles
10 to be employed are constructed somewhat differently from the crown tiles which have been described. In this instance the tiles embody a front portion 13 and a right angularly extending portion 14' which terminates
15 in a hook formation 25. The length of the portion 14' is such that when the tile is installed in position by inserting the hook portion 25 between the end of the portion 16 of the upper tile and the brace member 19 that
20 the tile will be retained in position. Brace members 19, identical with those secured to the crown tiles are secured to the remaining tiles in substantially the same manner as that in which the brace members are secured to
25 said crown tiles. As is apparent from the drawings, the portion 21 of the brace members 19 is disposed so as to lie below the extent of the tile, that is, the surface 21 will be positioned behind the next lowest tile. These surfaces 21 are secured to the wall 10 by the securing elements 24 in the manner described. The foregoing construction is carried out until the surface is covered to a point adjacent the floor and at this point the base tiles
30 are secured in position.

These base tiles include a front surface 13' and an upper surface 14' which has a hook portion 25. The surface 14' and the hook portion 25 are identical with those portions of the tiles described. However, the front surface 13' terminates in a portion 26 which extends at right angles to the surface 13' in a direction opposite from that in which the portion 14' extends and this portion 26 is
40 adapted to engage the floor 27. Suitable openings 28 are provided in the portion 26 and suitable securing elements such as the screws 29 extend from these holes into the floor 27 so as to secure the tiles in position.

45 In Fig. 7 a modified form of the invention is illustrated and the modification includes forming right angularly extending lips on the sides of the tile. At one end of the tiles a right angularly extending lip 30 is provided
50 which is adapted to be of a length equal to the portion 16. On the side opposite that to which the lip 30 is connected a lip 31 is provided which includes a hook formation 32 which is of a height equal to and which is formed substantially similar to the hook formation 25 on the portion 14'. It is apparent that this formation will effectively seal the abutting side edges of the tile and will serve to produce a more serviceable structure
60 and will also add to the rigidity of the construction. While I have shown this construction as a modified form of the invention it is to be understood that due to its advantageous properties its usage will be prevalent. This side wall construction will be pro-

vided on all three styles of tile. The matter of forming these side edges will be apparent to anyone skilled in the art.

It is apparent from the foregoing that I have provided a wall covering comprised of tiles which may be expeditiously installed and which will be so arranged so as to prevent water and other substances from entering into the space behind the tiles and due to the mounting employed it is apparent that the tiles may be very expeditiously cleaned. It is to be understood that if so desired a suitable plastic material might be introduced between the surfaces 16 and 14' so as to further insure a more complete seal therebetween for the purpose described.

While I have illustrated and described the preferred form of construction for carrying my invention into effect, this is capable of variation and modification, without departing from the spirit of the invention. I, therefore, do not wish to be limited to the precise details of construction set forth, but desire to avail myself of such variations and modifications as come within the scope of the appended claims.

Having thus described my invention what I claim as new and desire to protect by Letters Patent is:

1. A wall covering of the class described including a member embodying a substantially flat surface and parallel portions disposed to extend at right angles to said flat surface, certain of said parallel surfaces including securing means, and a brace member secured to the flat surface of said member on the rear side thereof having a portion adapted to be secured to the wall.

2. A wall covering of the class described including a plurality of members adapted to be disposed in juxtaposed horizontal rows, said members including substantially flat surfaces adapted to be disposed in a plane in spaced relation with a wall and parallel portions adapted to extend toward said wall substantially perpendicular to said flat surface, said perpendicular surfaces embodying means on the engaging walls of said juxtaposed members for interlocking said members, and braces secured to the rear side of said flat portions adapted to extend below the confines thereof and to be secured to said wall for fastening said members thereto.

3. A wall covering of the class described including a plurality of members adapted to be disposed in juxtaposed horizontal rows in spaced relation to a wall, the members of the uppermost row including flat surfaces and portions disposed to extend toward said wall substantially at right angles to said flat surfaces, the upper of said portions including a downwardly extending portion disposed substantially parallel to said flat surface in abutment with said wall and having a serrated edge, means for securing said members to said

wall adapted to extend through the serrations in said edge, the lower of said right angularly extending portions being foreshortened, and the next succeeding row of members including means adapted to engage said foreshortened portions for securing said members in position.

4. A wall covering of the class described including a plurality of members adapted to be disposed in juxtaposed horizontal rows in spaced relation to a wall, the members of the uppermost row including flat surfaces and portions disposed to extend toward said wall substantially at right angles to said flat surfaces, the upper of said portions including a downwardly extending portion disposed substantially parallel to said flat surface in abutment with said wall and having a serrated edge, means for securing said members to said wall adapted to extend through the serrations in said edge, the lower of said right angularly extending portions being foreshortened, and brace members secured to the rear side of said flat surfaces having portions adapted to extend between said foreshortened portions and said wall and adapted to be secured to said wall, the next lower row of members including portions adapted to engage said foreshortened portions to lock said members in position.

5. A wall covering of the class described including a plurality of members adapted to

be disposed in juxtaposed horizontal rows in spaced relation to a wall, said members including flat surfaces and parallel portions adapted to extend toward said wall at right angles to said flat surfaces, the lower of said portions being foreshortened, brace members secured to the inner side of said flat surfaces adapted to extend past said foreshortened portions and adapted to be secured to said wall, the upper of said parallel portions including a formed edge adapted to engage said foreshortened portion and to be disposed between the end thereof and said brace member to interlock said members.

6. A wall covering of the class described including a plurality of members adapted to be disposed in juxtaposed horizontal rows in spaced relation to a wall, said members including flat surfaces and parallel portions adapted to extend toward said wall at right angles to said flat surfaces, the lower of said portions being foreshortened to define a space between said portions and said wall, the upper of said portions including a formed edge adapted to engage said foreshortened portions to interlock said members, the lowermost row of said members having a portion adapted to be secured to the floor supporting said wall.

In testimony whereof I affix my signature.

ALFRED GOODELL.
